US0D1054889S

(12) **United States Design Patent** (10) **Patent No.:** **US D1,054,889 S**
(45) **Date of Patent:** **** Dec. 24, 2024**

(54) **INSULATION RESISTANCE TESTER**

(71) Applicant: **Chauvin Arnoux**, Asnieres-sur-Seine (FR)

(72) Inventor: **Alexandre Souillard**, Annecy (FR)

(73) Assignee: **Chauvin Arnoux**, Ansieres-sur-Sein (FR)

(**) Term: **15 Years**

(21) Appl. No.: **29/871,033**

(22) Filed: **Feb. 10, 2023**

(51) LOC (14) Cl. **10-04**

(52) U.S. Cl.

USPC **D10/78**

(58) **Field of Classification Search**

USPC **D10/78**

CPC G01R 27/025; G01R 31/52; G01R 31/129

See application file for complete search history.

(57) **CLAIM**

The ornamental design for an insulation resistance tester as shown and described herein.

DESCRIPTION

FIG. 1 is a top perspective view thereof;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.

The broken lines in the drawings depict portions of the insulation resistance tester which form no part of the claimed design.
